NOVELTY DISPLAY

Marie Y. Ogg, Lincoln Park, N. J.

Application July 17, 1936, Serial No. 91,091

1 Claim. (Cl. 40—126)

The present invention relates to a novelty display, one object thereof being the provision of a novel form of design which simulates a doll's head, which in itself is of unique appearance and readily attached to various forms of carrier mediums, such for instance as greeting cards, place cards, compacts, and the like.

Another object of the invention is the provision of a novel construction of head simulating member, which is simple, inexpensive and practical, and which lends itself to use upon numerous present day carrying members, the member being primarily made from a circular disk, in the nature of a button, in which only two openings however are provided, and which constitute the eye portions thereof, to be used with a background, upon which is painted, printed or otherwise formed the iris of the respective eyes.

In the accompanying drawing:—

Figure 1 is a plan view of the device per se.

Figure 2 is a section taken on line 2—2 of Fig. 1.

Figure 3 is a plan view of the device used as a valentine, dotted lines illustrating another shape the same can take.

Figure 4 is a plan view of another type when used as a place card.

Figures 5, 6, 7, and 8 illustrate other forms it may take.

Referring to the drawing, the numeral 10 designates a disk shaped support, which may be made of any relative stiff material, but preferably paper, and upon this is printed, painted or otherwise placed the two dots 11, which as will presently appear simulate the iris of each of the two eyes. Adhesively or otherwise attached to the disk 10, is a circular insoluble button-like disk 12, of relatively greater thickness than the disk 10, the same being provided with two openings 13, here shown circular in form, and through which the iris simulating dots 11 are visible. The exposed portion of the disk 12 forms the face of the doll, and upon it is formed in any desired manner, the mouth 14, the nostrils, and the eye brows, to complete the face, while the fibrous material 15, is adhesively attached to the support 10 and the adjacent portion of the disk 12 and simulates the hair of the doll.

It is thus seen that by making the head as described, that the same may be utilized with various carriers, such for instance as the heart shaped member 16, to form a Valentine's day place card, or a valentine per se in Fig. 3, with merely the lateral support 17, or the main card 18, dotted lines. And if so desired the bow 19, may or may not be used, and the body or arms of the doll may be printed, painted or otherwise be shown.

As shown in Fig. 4, the place card 20 is provided with a hat forming portion 21, adjacent to which is attached to the doll head device, the body simulation 22, as shown, while in Fig. 5, another form is shown wherein the picture presented may be used at graduation dinners, the doll carrying a degree scroll and having the mortar board hat.

In Fig. 6 a top hat 23, carries the doll head, while in Fig. 7, an Irish hat 23', for use on St. Patrick's Day, carries the doll head.

Various other forms may be used, as for instance where in Fig. 8, is shown the doll head attached to a gauze support, 24, which may or may not be alone or attached to a compact 25, or powder puff.

From the foregoing description, it is evident that the present invention may be used with many carrying members, and that it is a very novel and attractive device for use with many occasional novelties.

What is claimed, is:—

A novelty display, including a main supporting sheet like member, a second sheet like support attached thereto and having two spaced circular dots, a circular relatively thick insoluble disk having two spaced openings of a size greater than the sizes of the circular dots attached to the second sheet so that the dots are visible through the respective openings of the disk, said dots and openings simulating two eyes, the exterior of the disk being provided with other elements to simulate a face, and a tuft of fibrous material adhesively attached to the second sheet and arranged loosely about one edge of the disk to simulate the hair of the head formed by the disk.
